UNITED STATES PATENT OFFICE.

WILLIAMS G. MILLIGAN, OF AKRON, OHIO.

DEFLECTOR.

Application filed June 14, 1923. Serial No. 645,274.

To all whom it may concern:

Be it known that I, WILLIAMS G. MILLIGAN, a citizen of the United States, and a resident of Akron, county of Summit, State 5 of Ohio, have invented certain new and useful Improvements in Deflectors, of which the following is a specification.

This invention relates to improvements in defectors or guards, particularly adapted, 10 though not necessarily limited, for Ford automobiles.

In the well known types of automobiles, the control levers and pedals operate through slots in the foot boards. The presence of these slots or openings has caused considerable discomfort to the operators by allowing the entrance of heated air from the engine in summer and cold air in winter, as well as dust and dirt at all times.

20 The present invention has for its main object the provision of a deflector or guard to preclude the air from entering the machine, without interfering with the operation of the control levers.

25 A further object is to provide a deflector which may be readily applied in proper position, which will be durable in construction and which may be manufactured at a comparatively low cost.

30 The various features of my invention will be best understood from a description of the embodiment thereof selected to illustrate the same, it being understood, however, that my invention is not limited to such selected embodiment.

In the drawings accompanying this description:

Figure 1 is a side elevation of the deflector in position, the engine and body being broken away;

Figure 2 is an end elevation;

Figure 3 is a plan view of the deflector to cover the foot lever slots;

Figure 4 is the side elevation thereof;

Figure 5 is the end elevation thereof;

Figure 6 is an end elevation of a modification of a deflector for the foot lever slots;

Figure 7 is a plan view of the deflector shown in Figure 6; and

50 Figure 8 is a side view of the deflector.

Referring more particularly to the drawings, the numeral 2 designates the usual foot board comprising the removable sections 4 and 6 provided with registering slots 55 through which the clutch operating pedals

8 and 10 and the brake operating pedal 11 extend.

In order to prevent a blast of air from entering through these slots, I have provided the deflector shown in the drawings. The 60 deflector is preferably of sheet metal and arranged in two sections 12 and 22, each section being secured to the lower face of the removable floor section. The part 12 consists of a downwardly inclined front wall 14 65 and side walls 16 and 18, the latter being broken away to afford sufficient clearance for the transmission case. A flange 20 extends around the upper edge of the section 12, whereby it may be secured directly to 70 the floor board 4. Lugs 21 may be stamped up from the sections 12 to engage the slots and position the deflector. The rear section 22 consists of a rear wall 24, a short deep side wall 26 and a longer shallow wall 75 27, the wall 27 fitting against the inclined surface of the transmission casing. The sections are constructed to provide an opening 28 large enough to receive the shanks of the control pedals when the parts are assembled. 80 Lugs 29 may be provided on the section 22 to engage the slots and position it properly on the floor boards.

From the above description it will be manifest that any current of air directed against 85 the front and sides of the deflector will be directed away from the slots in the floor board, while, at the same time, there will be no interference with the free operation of the pedals.

90 The device for closing the hand lever slot is not claimed in the present application.

A modified form of a deflector for the foot lever slots is shown in Figures 9 and 10. A one piece frame is shown at 44, of 95 rectangular shape, which may have prolongations bent to provide hooks 46 to be secured to the transmission casing, or it may be provided with lugs 46^a, as shown in Figure 10, to be fastened to the top floor board 100 4 in any suitable manner. Either fastening means may be used as desired. If the hooks 46 are used, a strip of metal 23, bent as shown in Figure 11, may be added to the top floor board to hold the upper edge of 105 the frame. A second strip 23^a may be secured to the lower floor board to hold the lower edge of the frame. Upon the frame is fastened a flexible deflecting body 47 which may be of any suitable material, such 110

as metal or cloth, and including a cover part 48 which is inclined rearwardly and shaped toward an opening 50 provided therein to receive the shanks of the pedal. A wall 52 5 encloses the deflector at the rear. The deflector is placed around the foot levers and retained in place by any of the means described. When the foot boards are assembled, the deflector will be held tightly against 10 the lower face thereof by the frame 44. Inasmuch as the deflector will completely enclose the pedals, it is evident that the air currents will be directed downwardly by the inclined cover 48 and prevented from entering through the slots in the foot board.

Since the manner in which the different parts operate to perform their functions has been fully set forth, no further description of the operation is necessary for an understanding of the invention.

Having described the invention, what I claim as new and desire to secure by Letters Patent of the United States is:

1. In an automobile construction, the combination of a sectional floor board having slots therein for the operation of the control levers, a deflector having a front and side walls about the slots, means for suspending the deflector from one of the sections of the floor board, one of the side walls of the deflector extending rearwardly beneath the other section of the floor board, and a supplementary deflector upon the other section of the floor board cooperating with the first deflector to completely surround the slots.

2. In an automobile construction, the combination of a sectional floor board having slots therein for the operation of the control levers, a deflector having a front and side walls about the slots, means for suspending the deflector from one of the sections of the floor board, one of the side walls of the deflector extending rearwardly beneath the other section of the floor board, and a supplementary deflector upon the other section of the floor board cooperating with the first deflector to completely surround the slots, the lower portion of the deflector being closed by the transmission casing.

3. In a motor vehicle, the combination of 50 a pair of removable foot boards provided at adjacent edges with registering slots for controlling levers, and a deflecting device comprising two independent sections, one applied to each floor board, the front section having a rearwardly and downwardly inclined face, side walls integral with said face, one of said walls terminating at the rear edge of the front foot board, the rear section having a rear wall and a forwardly 60 extending side adapted to telescope within the front section when the boards are assembled, the sections affording an opening in the bottom of the deflector to receive the levers and being broken away upon the inner side to fit around the transmission casing.

4. In a motor vehicle, the combination of a pair of removable foot boards provided at adjacent edges with registering slots for the controlling levers, a guard for said slots, the 70 said guard comprising separable metallic sections secured on opposite sides of the slots to the respective floor sections, the front section being provided with a rearwardly inclined face projecting beneath the slots and shaped to direct air currents downwardly therefrom, the rear section having a rear wall and a short side portion adapted to telescope within the front section, the bottom of a section being broken away to afford an 80 opening in which the controlling levers operate.

5. In a motor vehicle, the combination of a pair of removable footboards provided at adjacent edges with registering slots for the controlling levers, and a guard for said slots, the guard comprising separable sections secured to the respective floorboards, the front section being provided with a rearwardly inclined face projecting beneath the slots and shaped to direct air currents downwardly therefrom, the rear section adapted to be receive within the front section, the bottom of a section being broken away to afford an opening in which the controlling levers operate.

WILLIAMS G. MILLIGAN.
